UNITED STATES PATENT OFFICE.

HENRY ROBERTS, OF PITTSBURG, PENNSYLVANIA.

APPARATUS FOR PICKLING WIRE.

SPECIFICATION forming part of Letters Patent No. 268,130, dated November 28, 1882.

Application filed June 16, 1882. (No model.)

To all whom it may concern:

Be it known that I, HENRY ROBERTS, of Pittsburgh, in the county of Allegheny, in the State of Pennsylvania, have invented certain new and useful Improvements in Apparatus for Pickling Wire, of which the following is a specification.

The improvements relate to the provisions for manipulating the wires in bundles, in connection with the pickling operation. The wire is formed of coils of nearly uniform diameter. This is done in the act of drawing, each length of wire being a bundle composed of a great number of coils held together by a few turns of the same, or a different wire around the several coils, to hold them together.

I provide a number of simple reels of wood, each adapted to be stood on end and to receive the bundles of wire by their being successively dropped or lowered from above. The lower portion of each reel receives four or other convenient number of suitable pins, each being received in a corresponding radial hole. These holes are bushed with copper, either to the whole depth of each or to a sufficient portion of the depth to protect the hole against destruction in pulling out and inserting the pins. An eye is formed in the outer end of each pin to facilitate pulling it out. The upper end of each reel is equipped for conveniently engaging a hook or other lifting device therewith, whereby the whole may be raised and lowered.

In the use of the invention six or other convenient number of bundles of wire are placed on each reel, so that they rest their weight on the pins, which project out near the bottom of the reel. Then the whole is engaged by a connection from a crane or other suitable carrier, and is lifted and traversed over a pickle-tub and lowered therein. After resting therein for a sufficient time the same or other lifting apparatus is brought into action to lift out the reel, with its load of wire. The wires are disengaged from the reel at the close of the operation by drawing out the pins and subsequently lifting out the reel, leaving the bundles of wire resting upon each other. They may receive the necessary bath of lime-water to neutralize the remaining acid by pouring the alkali upon the wires while the latter are in the piled condition in which they are left by the

removal of the reel, or in any other way. It is difficult to draw out the pins while the weight of the several bundles of wire is resting thereon. The drawing out of the pins under such condition would tend to injure the points of the pins and the mouths of the holes. I avoid this by providing a stand, suitably formed, to support the lowermost bundle a little higher than the pins. Spaces are provided in the stand to allow for the pins. The wires are disengaged from the reel at the close by drawing out the pins and setting the coils of wire free.

The following is a description of what I consider the best means of carrying out the invention.

The accompanying drawings form a part of this specification.

Figure 1 is a central vertical section, and Fig. 2 a plan view, of my improved device.

Similar letters of reference indicate like parts in both the figures.

A is the reel, which may be in a single piece, the wings or surfaces which touch the bundles of wire being of just the right diameter.

A' is the bail—a cross-bar of copper extending through a sufficient central recess in the upper end.

A² are bushings of copper tubing fitted around holes bored radially near the lower end.

D are pins, of copper, having each a head or eye at its outer end to facilitate withdrawal.

The several bundles of wire are marked m.

In loading the reel it is simply set on end with the pins D in place, and the coils or bundles of wire are put on and allowed to rest on the pins. In lifting, all are lifted together by the bail. In resting in the pickling-tub, all may stand on the bottom of the tub, in the same manner as all stood on the floor when loaded, the pickle, permeating all the interstices from within as well as without, being freely admitted by the grooves between the wings to the space between the bundles and the reel, both from below and above.

The stands may be made of wood or other material of reasonable strength which will endure the acid. I have in my experiments made the stands of cast-iron. Each is composed of a base, G, with a series of uprights, G', standing therein, of sufficient height and properly

arranged to support the lowermost bundle of wire between the several pins and allow a sufficient central space for the reel, and also liberal spaces for the several pins. When the reel, with its load of wire, is lowered down upon the stand, being turned a little, if required, to bring the pins into the spaces provided for them, the uprights G' take the entire weight of the bundles of wire off the pins D , which may then be easily withdrawn and the reel lifted out, leaving the coils resting on the uprights G' . The alkaline wash may be poured over the bundles in their regularly-piled condition on the stand $G G'$, there being a sufficient number of the stands to allow the work to proceed and to allow a liberal time for the alkali to penetrate all the spaces; or, if preferred in any case, the bundles of wire may, after the removal of the reel, be lifted off the stand and laid regularly or otherwise on the floor, or in a tank, to receive the alkali. The entire series of bundles, with the reel and its pins, may be lowered into a bath of alkali, if preferred. The stand supports the entire pile of bundles firmly and truly on the stand and relieves the pins entirely, allowing the latter to be quietly and gently drawn out and the pile of bundles to stand undisturbed, if so preferred, when the reel is lifted out.

Modifications may be made in the forms and proportions without sacrificing the advantages

of the invention. What I have termed the "reel" (marked A) may be in various forms. Instead of filling nearly all the space within the coils of wire it may be of much smaller diameter. Parts of the invention may be used without the others. I make a reel of iron to be used at a high temperature in the annealing and subsequent handling, and employ a stand identical with the stand $G G'$ to be used in the unloading thereof. In such case the bushing A^2 may be omitted; but pins identical with the pins D may be used.

I claim as my invention—

1. The reel A , with its removable pins D and lifting-bail A' , in combination with the stand $G G'$, adapted to serve relatively to each other and to the series of bundles of wire m , as herein specified.

2. The pins D and bushings A^2 in the reel A , arranged to serve relatively to the bundles of wire and to the stand $G G'$, as herein set forth.

In testimony whereof I have hereunto set my hand, at New York city, this 9th day of June, 1882, in the presence of two subscribing witnesses.

HENRY ROBERTS.
